(57) **CLAIM**

The ornamental design for an electronic shelf label as shown
and described.

DESCRIPTION

1.1 is a front view of an electronic shelf label;

1.2 is a rear view thereof;

1.3 is a left side view thereof;

1.4 is a right side view thereof;

1.5 is a top plan view thereof;

1.6 is a bottom plan view thereof;

1.7 is a front perspective view thereof; and

1.8 is a rear perspective view thereof.

2.1 is a front view of an electronic shelf label;

2.2 is a rear view thereof;

2.3 is a left side view thereof;

2.4 is a right side view thereof;

2.5 is a top plan view thereof;

2.6 is a bottom plan view thereof;

2.7 is a front perspective view thereof; and

2.8 is a rear perspective view thereof.

3.1 is a front view of an electronic shelf label;

3.2 is a rear view thereof;

3.3 is a left side view thereof;

3.4 is a right side view thereof;

3.5 is a top plan view thereof;

3.6 is a bottom plan view thereof;

3.7 is a front perspective view thereof; and

3.8 is a rear perspective view thereof.

4.1 is a front view of an electronic shelf label;

4.2 is a rear view thereof;

4.3 is a left side view thereof;

4.4 is a right side view thereof;

4.5 is a top plan view thereof;

(Continued)

4.6 is a bottom plan view thereof;
 4.7 is a front perspective view thereof; and
 4.8 is a rear perspective view thereof.

1 Claim, 32 Drawing Sheets
